3 Claims. (Cl. 36—37)

ABSTRACT OF THE DISCLOSURE

An improved heel construction involving a semi-rigid upper plate having one end secured to a lower resilient spring leaf which lies in contact with the inside heel of the shoe, the upper plate supporting a heel of a wearer, the spring leaf including a plurality of side wings which extend into actual sliding contact with the lower surface of the upper plate when supporting the heel of a wearer.

The present invention relates to an improved heel construction including an elastic support for shoe heels for men, women or children. The support of the present invention is fixed on the inside of the shoe at the level of the heel and designed to confer flexibility in walking.

The invention also relates to the assembly formed by a shoe and such an elastic support.

In more precise fashion the invention relates to an elastic support for shoe heels comprising a plate, called the upper plate, associated with another plate called the spring leaf, which has a part in contact with the shoe heel and is fixed to the latter.

The support of the present invention is characterized by the fact that the spring leaf, which is made of a material with good flexing characteristics, may be fixed at its front end to the upper plate and bent in such a way as to form a hinge.

The upper plate is made of a material that is pleasant in contact with the foot and flexible but strong enough to withstand folding. The spring leaf may be made of a plastic material (for example of "acetal") and the upper plate may be made of plastic material (for example of polypropylene).

Other characteristics and advantages of the present invention will appear in the following description, made in reference to the attached drawings, and giving, in purely explanatory but in no way limiting manner, two forms of embodiment of the support according to the invention.

Other objects and many of the attendant advantages of the present invention will be readily appreciated as the same becomes better understood by reference to the following detailed description when considered in connection with the accompanying drawings wherein:

FIGS. 1 to 4 relate to a first form of embodiment, of the elastic support according to the invention; and

FIGS. 5 to 7 a second form of embodiment.

FIG. 1 represents, alone, a spring leaf according to the invention.

FIG. 2 is an upper plate according to the invention.

FIG. 3 shows the elastic support constituted including the leaf of FIG. 1 and the plate of FIG. 2 fixed together and in the unfolded state.

FIG. 4 shows the support of FIG. 3 in perspective, as it appears ready for installation, finally.

FIGS. 5 to 7 show a second embodiment of the elastic support of the present invention in views similar to FIGS. 2 to 4. (The spring leaf of FIG. 1 can be suitable for this second form of embodiment.)

FIG. 5 is a plan view of a second embodiment of the upper plate;

FIG. 6 is a view similar to FIG. 3 showing the upper plate of FIG. 5 secured to the leaf of FIG. 1 in the unfolded state; and

2

FIG. 7 is a view of the assembly of FIG 6 as it appears ready for installation.

In these figures, reference is made to the attachment of spring leaf 2 to the upper plate 1.

5 The upper plate 1 is advantageously made of plastic material, for example of polypropylene, and the spring leaf 2, advantageously of plastic material itself, for example "acetal."

10 The spring leaf 2 of FIG. 1 has, at its front end (that is to say at its end which is, once the elastic support is installed in a shoe, at the front side of the shoe) a first set of two holes 3 and a second set of two holes 4 (this number of two holes for each set is not obligatory, however) and, at its rear part an opening 5.

15 The upper plate 1 of FIG. 2 has nipples 6 at the front part 13 on its face not visible in this figure, and it also has two holes 7 in the vicinity of the nipples 6 and a pin 8 at its rear part.

The assembly of the spring 2 on plate 1 is accomplished by introducing nipples 6 into the two holes 3 in plate 1, which insures a sufficient summary attachment for the presentation of the support for assembly.

20 As a matter of fact, the various holes and pins are disposed so that, when the nipples are engaged in holes 3, 25 the holes 4 of the spring leaf 2 are exactly opposite the holes 7 in plate 1. There is then introduced through the holes 4 and 7, nails or screws to make the attachment of the elastic support according to the invention to the shoe heel.

30 The fully assembled support, ready to be attached to a shoe, is folded at the front part of plate 1 to form a hinge 9 (FIG. 4).

If the nipples 6 are on the other face of the plate, two openings in the plate can be provided which come opposite nipples 6 when the support is folded again. This is done in order to avoid a superthickness.

35 If the elastic support is pinched, the pin 8 will be embedded in opening 5 and the support remains closed. This does not detract from any of the advantages of the support due to its flexibility and, on the contrary, gives it a more aesthetic appearance in the shoe. Note, moreover, that an elastic support that is too open can be annoying at the moment the foot is introduced into the shoe. Moreover, the pin 8 prevents any lateral movement of the upper plate with respect to the spring leaf.

40 A second embodiment of the support according to the invention is shown in FIGS. 5, 6 and 7. The spring leaf 2 can be the same as in the first form of embodiment (FIG. 1).

45 The upper plate 1 of FIG. 5 has two holes 10 in its front part 13, and a pin 8 in its rear part. The mounting of the spring leaf 2 on the plate 1 is done by placing the holes 10 of the plate opposite the holes 3 of the spring leaf and introducing, for example, rivets 11 in these pairs 50 of facing holes.

55 In contrast to the case of the first form of embodiment (FIG. 3), the spring leaf 2 is here fixed firmly and definitely to the upper plate 1. It remains to attach the spring leaf 2 to the heel of the shoe by introducing, for example, 60 nails or screws through holes 4. The remarks concerning the hinge 9 and the pin 8 remain applicable to this second form of embodiment.

65 The elastic support according to the invention is very flexible, very easy to install and quite low in cost.

60 In each form of embodiment of the invention, the upper plate 1 can assume two forms. It can be plane as well as convex in one direction or the other. It is particularly advantageous that it be concave with respect to the leaf 70 spring 2 (that is to say that it appears convex when it is placed on the shoe), because it then reinforces the effect of suspension insured by the spring leaf.

It goes without saying that the present invention is described by way of explanation and is in no way limiting, and that we can impart many modifications thereto without departing from its scope. For instance, the nipples 6 and the holes 3 can be in any number higher than two. The same is true of holes 4, 7 and 10. Furthermore, there is not necessarily a single pin 8 and a single opening 5. Pins 8 can belong to the spring leaf 2, with the openings 5 then being in plate 1. Finally, the nipples 6 and rivets 11 can be replaced by equivalent means.

The attachment of the leaf to the shoe heel can be done by nails, screws, hooks, etc. Moreover, the spring leaf 2 can be glued to the heel.

What is claimed as the invention is:

1. A resilient heel support for use in combination with a shoe having a heel and an inner sole, said heel support comprising in combination a semi-rigid upper plate supported on a flexing spring leaf positionable on said inner sole, said upper plate having an upper surface, a lower surface, a forward edge and a rearward edge, said spring leaf being concave toward the upper plate lower surface and including a plurality of side wings extending toward said upper plate lower surface, said spring leaf being secured to said upper plate by securement of the front edge thereof to the forward edge of said upper plate, the outer edges of said side wings freely resting in actual contact against the lower surface of said upper plate whereby when pressure is applied downwardly against the upper surface of said upper plate, said side wings will slide outwardly relative to said upper plate in actual contact there-

with to create a constant counter-pressure over a wide range of applied pressures.

5 2. The invention of claim 1 wherein said spring leaf has at one end at least one first hole and at least one second hole, said spring leaf and upper plate being brought together and fastening means passing through said first hole and securing said spring leaf and said upper plate together, said spring leaf being adapted to be secured to said shoe by fastening means passing through said second hole, said upper plate being folded in a hinge to lie over said spring leaf with said upper plate also including at least one nipple which is received in said first hole.

10 3. The invention of claim 1 wherein said spring leaf includes an opening, with said upper plate including a 15 pin received in said opening to maintain said support in the lateral position.
